(57) **CLAIM**

The ornamental design for a medical instrument, as shown and described.

DESCRIPTION

FIG. 1 is a rear perspective view of a medical instrument showing a first embodiment of our new design;

FIG. 2 is a front perspective view thereof;

FIG. 3 is a front perspective view showing the medical instrument;

FIG. 4 is a front perspective view showing the medical instrument;

FIG. 5 is a front perspective view showing the medical instrument;

FIG. 6 is a right side view thereof;

FIG. 7 is a top view thereof;

FIG. 8 is a left side view thereof;

FIG. 9 is a rear view thereof;

FIG. 10 is a front view thereof; and

FIG. 11 is a bottom view thereof;

FIG. 12 is a rear perspective view of a medical instrument showing a second embodiment of our new design;

FIG. 13 is a front perspective view thereof;

FIG. 14 is a front perspective view showing the medical instrument;

FIG. 15 is a front perspective view showing the medical instrument;

FIG. 16 is a front perspective view showing the medical instrument;

FIG. 17 is a right side view thereof;

FIG. 18 is a top view thereof;

FIG. 19 is a left side view thereof;

FIG. 20 is a rear view thereof;

FIG. 21 is a front view thereof; and,

FIG. 22 is a bottom view thereof.

The broken line showing of the attached devices in FIGS. 3, 4, 5, 14, 15, and 16 is for environmental purposes only. All other broken lines show visible portions of the article not claimed. The broken lines form no part of the claimed design.

1 Claim, 16 Drawing Sheets
